UNITED STATES PATENT OFFICE.

GUSTAV PAGEL, OF STETTIN, GERMANY.

DRYING PLANT FOR BRICKS.

SPECIFICATION forming part of Letters Patent No. 770,186, dated September 13, 1904.

Application filed December 29, 1903. Serial No. 186,931. (No model.)

To all whom it may concern:

Be it known that I, GUSTAV PAGEL, a citizen of the German Empire, residing at 16^b Alexander street, Stettin, Germany, have invented 5 certain new and useful Improvements in the Construction of Drying Plants for Bricks, of which the following is a specification.

My invention relates to improvements in the construction of drying-compartments as 10 part of a brick-making plant; and its object is to make use of waste heat in the process of drying bricks and to avoid a cracking of the latter.

My improved construction is illustrated by 15 the drawings herewith, in which—

Figure 1 is a plan view, partly in section, of a portion of a brick-kiln and the drying-compartment and air-conduits. Fig. 2 is a vertical cross-section of the new construction on 20 the line A B of Fig. 1; Fig. 3, a vertical longitudinal section of the kiln portion of Fig. 1; Fig. 4, a cross-section of the same on the line C D of Fig. 3; and Fig. 5, a section of the drying plant on line E F of Fig. 2, with a plan 25 elevation of the rail-basement.

As the drawings show, the smoke escape from the kiln to the drying-chamber is provided at the bottom of the construction, the smoke-conduit S being laid below the bottom 30 of the drying-compartment, following the same along and terminating in a chimney Sch. Two lateral conduits Z feed the drying-compartment with dry and hot air. The conduits A draw the air off from the compartment, 35 join the smoke-conduit S, and terminate with the latter in the chimney Sch. Both the said conduits A and the portions of the air-suppliers Z which are under the drying-compartments are provided with sliding plates a b to 40 regulate the admission and exit of the air.

The position of the said sliding plates is shown by Fig. 5. Radiators c, fed by waste steam from the steam-engine of the establishment, are also provided. The air, which is heated 45 by passing through the kiln after the burned bricks have been removed therefrom, is conducted to the drying-compartment through the aforesaid feeding-conduits Z, the quantity of the hot air to be admitted being regulated 50 by the sliding plates or dampers b. In the

drying structure the hot air ascends and diffuses in the drying-room, the moisture in this room coming from the bricks piled therein mixing with the dry air. When the mixture is sufficient, the air impregnated with moist 55 vapors is drawn off through the aforesaid conduits A, provided on the outsides of the two feeding-conduits Z and terminating in the chimney, as aforesaid. The sliding plates a regulate the exit of the air, just as its admission 60 is controlled by the sliding plates b. The exit of the air is favored by the provision of the conduits A on the outside, which permits the air to precipitate its moisture in these conduits. The moisture collecting in the discharge-conduit may be conducted to a basin 65 f in any suitable way. Between each two sliding plates in the discharge-conduit there is a gap in the walls w w, upon which are mounted the rails that carry the brick-carriages w', 70 (see Fig. 5,) so that the moist air only is drawn to the aperture of the discharge-conduit A, and at the same time the air impregnated by the moist vapors combines with the hot air of the feed-conduit and the radiators, entering 75 through the said openings in the walls which support the rails, thus moistening the dry air and obviating a cracking of the bricks by protecting them from the approach of too hot or dry air. To eliminate the hygroscopic water 80 of the bricks, the latter are heated by radiators h, placed near the exit of the drying-compartment and fed direct from a steam-engine. The heating and desiccating process is supported by the escaping smoke being conducted just below the drying-compartment, from 85 which it is separated by a dome of cast-iron. The drying-compartment is shut off against the outside at both ends by tightly-closing sliding doors, which are opened for the feeding the room with bricks and for the discharge of the latter. These doors are commonly employed in drying-compartments, and I have therefore not shown the same, as their construction and location are well understood. 90

The brick-burning kiln is shown in top plan view at the upper part of Fig. 1, in vertical longitudinal section in Fig. 3, and in transverse vertical section in Fig. 4 and contains 95 the burning-chamber B, which extends along 100

both sides of the kiln and across the end of the kiln adjacent to the drying-compartment. The chamber B communicates with the conduit S by a lateral passage e' , which is controlled by a valve e , and the chamber B also communicates with the conduits Z Z by passages $d' d'$, which are controlled by valves $d d$, the stems of valves $d d$ and e projecting through the top of the burning-kiln, as shown 10 in Figs. 3 and 4.

What I claim as new, and desire to secure by Letters Patent, is—

In a plant for drying bricks, the combination of a kiln, a drying-compartment communicating with said kiln a smoke-conduit opening into the kiln and extending lengthwise under said compartment, supplementary con-

duits arranged under said compartment parallel with said smoke-conduit and communicating therewith and with a chimney at the outer end of said smoke-conduit and the supplementary conduits, air-conduits disposed between the smoke and the supplementary conduits, said air-conduits and said supplementary conduits being provided with grated 20 openings leading to said compartment substantially as described.

In witness whereof I have hereunto signed my name in the presence of two witnesses.

GUSTAV PAGEL.
